UNITED STATES PATENT OFFICE

92,114

DESIGN FOR A VELOCIPED

Richard V. Sawyer, Elyria, Ohio, assignor to
Hall Kirkham, Elyria, Ohio, receiver of The
Colson Company, Elyria, Ohio, a corporation
of Ohio

Application October 7, 1933, Serial No. 49,421

Term of patent 7 years

To all whom it may concern:

Be it known that I, RICHARD V. SAWYER, a citizen of the United States, residing at Elyria, in the county of Lorain, and State of Ohio, have invented a new, original, and ornamental Design for a Velocipede, of which the following is a specification, reference being had to the accompanying drawing, forming part thereof.

In the drawing, Fig. 1 is an elevation of a velocipede embodying my design; and Fig. 2 is a

perspective view on a smaller scale of the velocipede shown in Fig. 1.

An important feature of the design is the construction of the front fender or mud guard which conceals the front fork and produces a streamline effect.

I claim:

The ornamental design for a velocipede, substantially as shown and described.

RICHARD V. SAWYER.
